Atty's.

UNITED STATES PATENT OFFICE.

PEARL M. BURGESS, OF READING, MASSACHUSETTS, ASSIGNOR TO PEARL M. BURGESS AND JOSEPH BLACHER, DOING BUSINESS UNDER THE FIRM NAME OF BURGESS AND BLACHER, OF BOSTON, MASSACHUSETTS.

HOSPITAL OPERATING ROOM.

Application filed September 7, 1926. Serial No. 133,762.

This invention relates to a hospital operating room used during daylight, the operator's station being located in close proximity to a window, to secure sufficient light. It is customary to heat the room by a radiator located close to the wall and below the window, air from the lower portion of the room being heated by and ascending from the radiator.

10 The object of the invention is to protect the operator from radiated heat, and at the same time, maintain the air in the vicinity of the operator and a patient in a uniformly warmed condition, without subjecting the operator and the patient to drafts of air.

This object is attained by the construction and combination hereinafter described and claimed.

15 Of the accompanying drawings forming a part of this specification,—

Figure 1 shows in perspective, and partly in section, portions of the wall of an operating room and of a window therein, a radiator, and the semi-partition hereinafter described.

Figure 2 is a vertical section on line 2—2 of Figure 1.

Figure 3 is a fragmentary horizontal section, on line 3—3 of Figure 2.

20 The same reference characters indicate the same parts in all of the figures.

In the drawings, *a* designates an outer wall of an operating room, and *b* a window therein. *c* designates a radiator located 35 below the window and at the inner side of the wall above the floor *e*. *d* designates an operating table, located at the operator's station. The length of the radiator, is usually about equal to the width of the window.

40 Interposed between the radiator and the operator's station, is a substantially vertical semi-partition, separated by an air space from the window and radiator, the height 45 of the partition being such that its upper end is considerably above the operator's head, and below the ceiling of the room. The upper portion of the partition is of light-transmitting construction, so that light from the window may be transmitted to the operator's station. This portion preferably includes horizontal frame members 12, vertical frame members 13, and glass panes 15, supported by the frame members. The end

panes 15 may be set in frames connected by 55 vertical hinges 19 with the end members 13, as shown by Figure 1. The lower portion of the partition is of sectional construction, permitting access to the radiator, for the purpose of cleaning the same, it being essential that the surfaces of the radiator be kept 60 free from dust and dirt. This portion preferably includes the lower horizontal frame member 12, a bottom horizontal frame member 16, extensions 13^a of four of the vertical members 13, panels 17 slidable horizontally in overlapping relation with each other between the lower member 12 and the bottom member 16, and panels 17^a connected by vertical hinges 18 with the extensions 13^a of 65 two of the vertical members 13. Each panel may be displaced to expose a portion of the radiator and permit the removal of dust from the surfaces of the exposed portion thereof, the arrangement being such that all 70 portions of the radiator are accessible.

75 The partition is adapted to permit air in the lower portion of the room to flow into the lower end of the air space containing the radiator, the air flowing upward over the surfaces of the radiator, and over the upper end of the partition, into the upper portion of the room. I prefer to thus adapt the partition by elevating the bottom frame member 16, thereof, above the floor, thus 80 providing air passages under the partition, as shown by Figures 1 and 2. The partition as described, is adapted to be fitted in the inner side of an embrasure, the vertical end walls of which are designated by *ff*, the 85 window *b* being fitted in the outer side of the embrasure. The window *b*, the portion of the wall *a* below the window, the end walls *f* of the embrasure, and the partition, 90 collectively constitute a verticle flue, the lower end of which receives air from the lower portion of the room, the height of the flue being determined by the height of the partition.

95 I claim:

100 1. A vertical semi-partition supported in an operating room adjacent a window and a radiator below the window, the lower edge of the partition being supported above the floor, to permit air to flow under the partition to the radiator, the height of the partition being less than that of the room to 105 permit air to flow from the radiator above

the partition, the upper portion of the partition being of light-transmitting construction, while its lower portion includes movable sections normally closing said portion and displaceable to form openings therein permitting cleaning access to the radiator.

2. A vertical semi-partition as specified

by claim 1, the vertical edges of the partition being abutted against the vertical sides 10 of an embrasure containing the window and radiator.

In testimony whereof I have affixed my signature.

PEARL M. BURGESS.
